UNITED STATES PATENT OFFICE.

GEORGE E. GAY, OF AUGUSTA, MAINE.

SCREW-DRIVER.

SPECIFICATION forming part of Letters Patent No. 705,917, dated July 29, 1902.

Application filed April 10, 1902. Serial No. 102,196. (No model.)

To all whom it may concern:

Be it known that I, GEORGE E. GAY, a citizen of the United States, and a resident of Augusta, in the county of Kennebec and State 5 of Maine, have invented a new and Improved Screw-Driver, of which the following is a full, clear, and exact description.

This invention relates to improvements in screw-drivers of the ratchet type, the object 10 being to provide in such a screw-driver a single pawl, so arranged that it may be adjusted to cause a movement of the blade with the handle in either direction, the blade remaining stationary while the handle is turned in 15 the reverse direction or so adjusted as to form a lock between the blade and handle, so that the blade and handle will move together in either direction similarly to the ordinary fixed-blade screw-driver, which at times is 20 found convenient.

I will describe a screw-driver embodying my invention and then point out the novel features in the appended claims.

Reference is to be had to the accompanying 25 drawings, forming a part of this specification, in which similar characters of reference indicate corresponding parts in all the figures.

Figure 1 is a side elevation of a screw-driver embodying my invention. Fig. 2 is a partial 30 longitudinal section thereof. Fig. 3 is a partial longitudinal section at right angles to Fig. 2. Fig. 4 is a perspective view with a portion of the ferrule broken away. Fig. 5 is a section on the line $x-x$ of Fig. 3. Fig. 6 is a plan illustrating a cam employed, and Fig. 7 is a perspective view of the formed cam-ring.

Referring to the drawings, 1 designates the blade of the screw-driver, mounted to rotate 40 in the ferrule 2, attached to the handle 3. On the inner end of the blade 1 is a disk 4, provided on its inner surface with ratchet-teeth 5. Adapted to engage with the ratchet-teeth is a pawl 6, which extends across the 45 ferrule and has end projections 7, which pass through slots formed in the ferrule and are adapted to engage with an operating-cam, as will be hereinafter described. This pawl is guided by means of a pin 8, extended through 50 the ferrule and through a slot 9, formed at the center of the pawl. By means of this

slot the pawl may move transversely with relation to the guide-pin, as well as rock thereon, the object of which will hereinafter appear. The pawl, however, is held yieldingly 55 in engagement with the ratchet-teeth by means of a spring 10, here shown as attached to a stop-block 11, having a perforation through which the pin 8 passes, and this block engages with the inner surface of the 60 disk 4 to prevent inward movement of the blade into the handle or ferrule.

A sleeve 12 has a rotary movement on the ferrule 2, and it is limited in its movement by means of the pin 8, engaging with either 65 end wall of a slot 13, formed in the sleeve. On the inner side the sleeve 12 has a cam plate or ring having opposite cam-surfaces 14 and also opposite cam-surfaces 15, which are on a higher plane than the surfaces 14. This 70 cam-plate may be conveniently made of a strip of spring metal and sprung into place within the sleeve and held by means of lugs 16 on the sleeve engaging in perforations in the cam plate or ring. It is to be understood, 75 however, that it may be otherwise secured in place, or the sleeve may be stamped to form the cam-surfaces.

In operation in inserting a screw the blade 80 obviously will turn with the handle upon the right hand turning. For this purpose the sleeve 12 is to be rotated until the cam-surface 15 tilts one end of the pawl 6 upward and the opposite end engages with the ratchet-teeth. When in this position, the blade will 85 remain stationary upon a backward or reverse movement of the handle preparatory to another turning of the blade. In taking out a screw the sleeve is to be turned to raise the other end of the pawl to cause the opposite end to engage with the ratchet-teeth, and the same operation will take place, excepting the movements will be in the opposite direction to that first described. When it is desired to lock the blade and handle together 90 to operate as an ordinary screw-driver, the sleeve is to be turned until the pin 8 is in a central position in the slot 13, as indicated in Fig. 5. Then the pawl may be moved by the spring 10 to engage each of its ends with 95 teeth of the disk 4. This is permitted by the slot, which allows free play of the pawl trans-

versely of the pin. Obviously this cannot occur with a pawl merely pivoted to swing on a pin.

Having thus described my invention, I claim as new and desire to secure by Letters Patent—

1. A screw-driver comprising a ferrule, a blade mounted to rotate therein and having ratchet-teeth on the inner end of said blade, a guide-
10 pin extended transversely in the ferrule, a pawl having a slot through which said pin passes, whereby the pawl may swing on the pin and also move transversely thereof, and means for rocking the pawl to engage either
15 of its ends with the ratchet-teeth, substantially as specified.

2. A screw-driver comprising a ferrule, a blade mounted to rotate therein and having ratchet-teeth on its inner end, said ferrule
20 being provided with opposite slots, a pin extended transversely through the ferrule, a pawl extended across the ferrule and having a slot through which the pin passes, whereby the pawl may rock on the pin and also have a
25 transverse movement with relation thereto, projections on said pawl passing through the

slots of the ferrule, a sleeve mounted to rotate on the ferrule, and a cam on the inner side of said sleeve for rocking the pawl, substantially as specified.

30

3. A screw-driver comprising a ferrule, a blade mounted to rotate therein and having ratchet-teeth on its inner end, said ferrule being provided with opposite slots, a pin extended transversely through the ferrule, a
35 pawl extended across the ferrule and having a slot through which the pin passes, whereby the pawl may rock on the pin and also have a transverse movement with relation thereto, projections on said pawl passing through the
40 slots of the ferrule, a sleeve mounted to rotate on the ferrule, a cam on the inner side of said sleeve for rocking the pawl, and a stop-block engaging with the inner end of the blade, substantially as specified.

45

In testimony whereof I have signed my name to this specification in the presence of two subscribing witnesses.

GEORGE E. GAY.
